DUST COLLECTING APPARATUS

David Webber Kestell, Leicester, England, assignor to United Shoe Machinery Corporation, Flemington, N. J., a corporation of New Jersey

Application April 28, 1950, Serial No. 158,696
In Great Britain May 11, 1949

4 Claims. (Cl. 183—75)

1

This invention relates to dust collecting apparatus and is herein disclosed as embodied in a device suitable for use in cleaning dust from shoes.

During the manufacture of shoes having uppers of white leather, such as buckskin, it is necessary to take special precautions in order to minimize or prevent soiling of the leather. Some manufacturers protect the leather from soiling by coating it with French chalk, in either powdered or paste form, and either before or shortly after the uppers have been cut out from the skins. Additional quantities of powdered chalk may be applied to the uppers as they pass through the factory during the course of manufacture of the shoes. Before the shoes are packed for shipment, the uppers must be cleaned and, after the usual cleaning operation, it is customary to brush the uppers by hand to improve their appearance and also to insure the removal of any dust or any surplus cleaning material which may remain on the uppers. The dust which arises from this brushing should be disposed of to prevent its entering the atmosphere of the factory.

During the brushing operation, it is usually desirable to have on hand a small supply of chalk to which the operator has ready access in case he finds it necessary to apply the chalk locally to a shoe. This supply of chalk not only should be readily accessible to the operator but it should be provided in such a way as to avoid waste of the operator's time in replenishing it.

A similar hand brushing operation is also desirable in the finishing of suede shoes having uppers of a color other than white. These shoes because of the fibrous nature of the uppers are especially subject to the collecting of dust and it is desirable that the brushing operation be performed under conditions which will prevent the dust from entering the atmosphere of the factory. In this case, however, there is no necessity for a supply of chalk or dust to be available to the operator.

It is an object of the present invention to provide a dust collecting apparatus suitable for use in the brushing of dust from shoes, such apparatus having means for recovering and rendering readily available for use a portion of the dust removed from the shoes. An apparatus for this purpose which is illustrated herein comprises a casing which forms a cabinet-like structure and has a re-entrant space formed in its upper portion within which a shoe may be held while being brushed by hand. The upper portion of the casing thus constitutes a hood and means are

provided for causing a draft of air to enter the hood and to discharge from the lower portion of the hood. The dust entrained in the air current can be filtered by means provided within the casing or it can be conducted to a locality outside the factory and there discharged into the atmosphere.

In accordance with a feature of the invention, a tray is provided within the above-mentioned dust hood for receiving and rendering readily recoverable such dust as settles upon the tray from the dust-laden air passing through the hood. Preferably the hood is provided with a support upon which the tray is movable between two positions, in one of which positions a considerable portion of the dust-laden air passes over the tray and deposits dust thereupon, and in the other position substantially none of the dust-laden air passes over the tray.

These and other features of the invention comprising various combinations and arrangements of parts will best be understood from the following description of a preferred embodiment shown in the accompanying drawings, in which

Fig. 1 is an angular view of one form of an improved dust collecting apparatus embodying the invention;

Fig. 2 is a side elevation in section of the apparatus shown in Fig. 1;

Fig. 3 is a side elevation in section of a modified form of apparatus showing the various parts so arranged as to recover dust entrained in the air passing through the hood;

Fig. 4 is a view similar to Fig. 3 showing the various parts so arranged as to bypass the air passing through the hood when the recovery of dust is not desired; and

Fig. 5 is an angular view of the apparatus shown in Fig. 3.

The apparatus illustrated herein comprises a casing which forms a hollow cabinet-like structure having a re-entrant space formed in its upper portion to provide an open-front hood within which a shoe may be held by the operator while he brushes it. This casing comprises a left-hand outer side wall 1 (Fig. 1), a right-hand outer side wall 3 (Fig. 2), both walls being turned toward each other at their forward ends to form front walls 5 and 7 respectively, and a rear wall 9 which curves forward at its upper end portion. The casing has also a lower re-entrant space formed in its forward lower portion by a pair of parallel inner side walls 13 which extend rearwardly from the inner edges of the front walls 5 and 7, and a vertical wall 15 which

extends widthwise of the machine between the rear edges of the two inner side walls above mentioned. The walls 13 extend rearwardly for a distance sufficient to allow access of the legs of the seated operator and extend upwardly generally to about bench height, these walls being somewhat higher at their forward edges than at their rear edges, and having upper edges which extend downwardly and rearwardly. As shown in Fig. 2, the downward inclination of the upper edges is steeper along the rearward portions (indicated by the reference numeral 14) of the edges than along the forward portions (indicated by the reference numeral 16).

A closure member 17 joins the upper edges of the walls 13 and constitutes the upper wall of the lower re-entrant space. The forward portion of the closure member 17 extends downwardly and rearwardly at an inclination corresponding to that of the forward portions 16 of the upper edges of the walls 13, and the rearward portion extends downwardly and rearwardly at an inclination corresponding to that of the rearward portions 14 of the upper edges of the walls 13. The wall 15 has an opening which is normally closed by a removable panel 19, the purpose of which will be later explained. The rear wall 9 at its upper end portion curves forwardly to form in conjunction with the side walls 1 and 3 a hood-like structure.

The front of this hood-like structure has a large opening 20 through which a shoe may be inserted and held by the operator while he brushes it. Adjacent to the upper portion of the rear wall 9 and parallel thereto is a stationary baffle 21, the upper edge of which is somewhat above the top of the opening 20 and the lower edge of which is on substantially the same level as the forward edge of the closure member 17, thus providing a clear passage 23 through which a strong current of air may be set up which will pick up light dust tending to rise above the entrance opening of the hood.

The opening between the lower hollow interior portion of the casing and the upper re-entrant space (which is defined by the side walls 1 and 3, the baffle 21, and the closure member 17) is reduced widthwise by the provision of a pair of right and left angle pieces 25 (only the right-hand one being shown) secured to the outer side walls 1 and 3 and having horizontal flanges equal in width to the distances between the outer side walls and their respective adjacent inner side walls 13. These horizontal flanges lie in a horizontal plane which contains the forward edge of the closure member 17 and the lower edge of the baffle 21. Each of the angle pieces 25 has a turned down flange (not shown) by which it is secured to the adjacent side wall, and it has also a turned down flange 26 which is spaced from the adjacent side wall by the width of the horizontal flange. These vertical flanges 26 extend down from their horizontal flanges for a distance of about $4\frac{1}{2}$ inches except that those portions of the flanges which are forward of the wall 15 terminate at their junction with the closure member 17.

Four angular brackets 27 are secured respectively to the rear wall 9, the front wall 15, and the vertical flanges 26 of the right- and left-hand angle pieces 25, these brackets together forming a horizontal rectangular frame. The brackets 27 have depending vertical flanges 29 which define the opening between the upper re-entrant space and the lower hollow interior por-

tion of the casing. This opening is partially closed by an upper face 30 of a box-like structure, this upper face 30 having eight circular openings 31 formed in it. Attached to the upper face 30 and depending below each of the circular openings 31 is a filter bag 33. The box-like structure, above referred to, has four side walls 35 each of which is perforated with a plurality of holes 37 having diameters somewhat less than one-half an inch. The box-like structure has a base 39 which is not perforated. Extending widthwise across the top 30 of the box-like structure is a handle 41 for facilitating removal and replacement. The box-like structure is normally held in position within the casing by latch members 43 engaging with catch members formed on the right- and left-hand brackets 27.

An exhaust blower 45 is secured to a base closure wall 47 of the casing and is so arranged as to draw air down through the hood and through the filters and to exhaust it into a chamber 51 from which it passes through a series of baffles into the atmosphere.

Secured to each of the vertical flanges 26 of the angle pieces 25 is a horizontal bracket 53 in the form of an angle iron, these brackets being positioned above the brackets 27. The brackets 53 serve as supports upon which a dust collecting tray 55 can be moved forwardly or rearwardly to either of two positions. This dust collecting tray extends widthwise of the cabinet the full distance (allowing for reasonable clearance) between the vertical flanges 26 of the angle pieces 25. It is positioned some little distance above the level of the junction of the front wall 15 with the sloping closure wall 17 and its dimension forwardly and rearwardly of the apparatus is less than the distance between the walls 17 and 9 at the level of the tray, so that the tray does not obstruct the flow of air from the hood to the filtering device already described. The tray 55 has a rear wall 57 which extends up beyond the side walls of the tray and which terminates above the level of the lower edge of the baffle 21 to engage the baffle 21 as a stop. The tray 55 has a front wall 59 which inclines upwardly and forwardly and has a slope corresponding to that of the more steeply inclined rearward portion 14 of the closure wall 17.

In the operation of the apparatus, assuming the tray occupies the position shown in Figs. 1 and 2 of the drawings and the motor of the blower 45 is running, a current of air will be drawn into the upper hood-like portion of the casing and exhausted through the baffles out of the chamber 51. This air current will divide into three parts, one of which rises to the top of the hood and then descends through the space between the rear wall 9 and the baffle 21, another of which passes down through the opening between the rear wall 57 of the tray and the lower portion of the baffle 21, and the third part of which passes through the gap between the front wall 59 of the tray and the closure member 17. These three portions of the air current all pass down through the filter bags 33 and through the openings in the walls 35 and thence through the blower 45 into the atmosphere.

However, if the tray be moved rearwardly along the brackets 53 until its rear wall 57 engages the baffle 21, the air current flowing through the apparatus will be divided into only two parts, one of which flows through the space between the rear wall 9 and the baffle 21 and the other of which flows between the front wall 59 of the tray

and the closure member 17. Under these conditions substantially no dust will be deposited upon the tray. On the other hand, if the tray is moved forwardly along the brackets 53 until its front wall 59 engages the more steeply inclined portion of the closure member 17, the air current will again be divided into two portions, one of which passes between the rear wall 9 and the baffle 21 and the other of which passes between the lower edge of the baffle 21 and the rear wall 57 of the tray. Under these conditions dust will settle upon the tray from the air current which passes over it. The operator, therefore, when he is using the apparatus for the cleaning of shoes having white uppers coated with French chalk, will locate the tray in its forward position in order to accumulate a deposit of chalk in the tray and, when he operates upon suede shoes of various colors which have accumulated undesirable dust, he will move the tray to its rearward position to avoid having dust settle upon it.

A modified form of apparatus is shown in Figs. 3, 4 and 5. In this modified construction a baffle 61, corresponding to the baffle 21, is formed in two parts, 63 and 65, the part 63 being above the part 65 and being freely pivoted at its upper and forward edge on a pin 67 extending across the upper portion of the apparatus and secured at its ends to the walls 1 and 3. The lower portion 65 of the baffle 61 is pivotally secured to the lower edge of the upper portion 63 by a hinge 69 extending widthwise of the apparatus. This hinge permits the baffle to be moved into the broken position shown in Fig. 4 and into but not beyond the straight position shown in Fig. 3. The lower end portions of the baffle are notched, as indicated by the numeral 71 on Fig. 5, to fit over the angle pieces 25.

A rear stop or rest 73 and a forward stop or rest 75 are provided on the horizontal flange of each of the angle pieces 25 for engagement with the notched portions 71 of the lower baffle portion 65. Between the vertical flanges of the angle irons 25 the unnotched portion of the baffle member 65 extends down below the level of the horizontal flange of the angle iron 25 and terminates in an offset portion or lip 77 which, as shown in Fig. 4, is adapted to rest on the forward edge of the tray 55 when the baffle is in its forward position. A handle 79 is provided to facilitate adjustment of the baffle 61.

This form of apparatus may be provided with the filter bag 33, already described, or it may be connected, as shown, to the usual exhaust system with which many factories are provided. In such case the space below the tray 55 is closed by a dust-receiving pan 81 in the form of a funnel which directs the dust downwardly into an exhaust pipe 83. This arrangement may also be used if desired in that form of the apparatus illustrated in Figs. 1 and 3 and already described.

A fluorescent lighting tube 85 is provided in the upper portion of the casing in both forms of the apparatus as shown in Figs. 2, 3, 4 and 5.

In using the apparatus shown in Figs. 3, 4 and 5, the operator, if he desires to collect dust in the tray 55, will draw the tray forward into the position shown in Fig. 3 and he will position the baffle 61 against the rear stops 73, as shown in that figure, to enable the air current to pass over the tray on its way to the exhaust system. If, however, he does not wish to collect dust in the tray, he will grasp the handle 79 and raise the entire baffle 61 into the position shown in dot-dash lines in Fig. 4 and at the time will push

the tray rearwardly into the position shown in that figure. He will continue to draw the baffle member 65 forward, raising the lip 77 over the forward edge of the tray and letting it rest there.

5 The forward stops 75 will prevent forward sliding of the baffle member 65. When the tray and the baffle are in this position the air current will not pass over the tray and no dust will be deposited thereon.

10 Having described my invention, what I claim as new and desire to secure by Letters Patent of the United States is:

1. In a dust collecting apparatus, a suction dust hood having a front opening communicating with a downwardly directed throat, a tray partially blocking the throat for receiving and rendering readily recoverable such dust as settles upon it from a current of dust laden air passing down through the throat, and a support upon which 15 the tray is movable forwardly and rearwardly across the throat, the dimension of the tray in the direction of its movement being less than the corresponding dimension of the throat to leave an unblocked path rearwardly of the tray 20 when the tray is in a forward position on its support and forwardly of the tray when the tray is in a rearward position, said tray serving when in its forward position to cause the current of dust laden air to pass over it and deposit dust upon it and when in its rearward position to cause the current of dust laden air to by-pass it.

2. In a dust collecting apparatus, a suction dust hood having a passageway through which dust-laden air can be withdrawn, a tray extending partially across said passageway for receiving and rendering readily recoverable such dust as settles upon it from the dust-laden air passing through the passageway, a support upon which the tray is movable between two positions, in 25 one of which positions a considerable portion of the dust-laden air passes over the tray and deposits dust thereupon, and in the other position the dust-laden air by-passes the tray, and a baffle forming a second passageway connecting the upper portion of the dust hood with the first-mentioned passageway at a locality rearward of the tray to dispose of light dust which rises from the work, said baffle being movable to shield the tray from dust when the tray is in a position to be by-passed and to permit access of dust to the tray when the tray is in dust-receiving position.

3. In a dust collecting apparatus, a suction dust hood having an entrance chamber in which dust can be brushed from shoes and having also a throat leading down from said entrance chamber for conducting dust-laden air therefrom, said entrance chamber communicating with said throat through a substantially rectangular opening, a rectangular tray extending substantially across the full width of said opening, the forward and rearward dimension of said tray being less than the corresponding dimension of the opening to leave a space in the opening through which dust-laden air can enter the throat, and a support on which the tray is movable forwardly and rearwardly to vary the position of the space just mentioned, said space being to the rear of the tray when the tray is in its forward position, whereupon dust-laden air in passing over the tray to reach said space will deposit dust upon the tray, and said space being forward of the tray when the tray is in its rearward position, whereupon dust-laden air will enter the throat directly through said space without passing over said tray.

4. In a dust-collecting apparatus, a suction dust hood having a passage through which dust-laden air can be withdrawn, a tray within said dust hood for receiving and rendering readily recoverable such dust as settles upon it from the dust-laden air passing through said passage, and a baffle in said hood movable between two positions, in one of which positions the baffle allows the air current to pass over the tray and to deposit dust thereupon, and in the other of which positions the baffle causes the air current to bypass the tray without passing thereover.
